UNITED STATES PATENT OFFICE.

ALBERT J. CAMPBELL, OF MARION, IOWA, ASSIGNOR TO NELLIE KITCHING, OF MARION, IOWA.

TRAIN-SERVICE COUPLING.

1,278,850.

Specification of Letters Patent. Patented Sept. 17, 1918.

Application filed April 20, 1918. Serial No. 229,720.

To all whom it may concern:

Be it known that I, ALBERT J. CAMPBELL, a citizen of the United States, residing at Marion, in the county of Linn and State of Iowa, have invented certain new and useful Improvements in Train-Service Couplings; and I do hereby declare the following to be a full, clear, and exact description of the invention, such as will enable others skilled in the art to which it appertains to make and use the same.

This invention relates more particularly to train-pipes used for air-brakes, and has for its object to provide means in connection with said pipes whereby telephonic communication may be had from end to end of the train.

The invention embodies certain improvements in the device for which Letters Patent No. 1,169,459 were issued to me on the 25th day of January, 1916, and to which reference may be had.

The specific object of this invention is to provide for a complete electrical circuit by way of the train pipe, instead of, as in the former patent, depending upon ground connections to complete the circuit.

The full nature of the invention is disclosed in the description and claims following, reference being had to the accompanying drawing, in which:—

Figure 1 is a plan view of a coupling embodying my invention, one of the heads being shown in exterior outline and the other mainly in section. Fig. 2 is a side view of the head shown in section in Fig. 1, with the central packing ring in position. Fig. 3 is a fragmentary view of the same, without said ring, and partly in section, the better to illustrate the wiring. Fig. 4 is a view of the inner side of the clench member shown in Fig. 2.

In the drawing, the numeral 1 denotes the flexible portion of a train-pipe such as supplies air for the operation of the brakes. This pipe is provided at its free end with a head 2, which with the attached part 3 to be described presently forms one half of the coupling. These interlock to couple by being placed side by side and given about a quarter turn, in a manner familiar to all trainmen. By this action the extension flange 4 passes on the inner side of the keeper 5, and with a wedging action tending to force the halves of the coupling into

close contact. This does not differ in any important respect from the action of couplings in general use, and needs no particular description, except as will appear hereafter.

In my improved coupling, the part 3, which may for convenience be called the knuckle, is a separate part from the one attached to the pipe, and is carefully insulated therefrom. Between the flat faces of the parts is interposed a piece of insulation 6, such as wood fiber, and through this and the adjacent parts pass bolts 7. These too are suitably insulated, as by thimbles 8 and washers 9, so that no current can short circuit from one part to the other. There is also left a gap between the rear end of the part 3 and the expanded tubular portion of the other member, and which is designated by the numeral 10. Where corresponding heads join to make the air-tight pipe union, slightly flexible rubber rings 3^a serve the double purpose of gaskets and for insulation.

In each complete head so formed, and which constitutes the half of a complete coupling, is seated a pair of conducting wires 11 and 12, the former passing through a cored passageway 13 and out through a hole 14 to the inner side of the flange 4, and uniting by branches with copper terminals 15 whose heads project a little way from the outer face of said flange. The other conductor is led through a passageway 16 in the knuckle to a copper terminal 17, which when the parts are in coupled position makes contact with one or both of the terminals above described. The insulated wires pass back through grooves in the tubular portions of the heads to the insides of the pipes, and are supposed to run from head to head at opposite ends of the cars. It will of course be understood that when the terminal hose-pipes 1 are secured to the heads they are drawn so firmly thereon as to make air-tight joints.

The effect of this construction is to provide a double line of wires, which may extend from end to end of a train, and which may be employed for connecting the ends of the train by telephone, the advantage of which is clearly set forth in the former patent above referred to. The advantage of this special construction is that it dispenses with any ground connection, and thus eliminates the noise that might be incident to such

construction. It also avoids the possibility of short-circuiting the telephone by power currents or signal currents passing through the rails, and which might prove injurious to the telephone or the operator.

Having thus described my invention, I claim:

1. Combined with a train-pipe, terminal heads therefor comprising in each an air-passage member and a separate locking knuckle attached thereto and electrically insulated therefrom, and duplicated electrical conductors leading from each knuckle at one end of the service pipe to the other member at the other end thereof, substantially as and for the purpose set forth.

2. Combined with a train-pipe, a head for each end thereof, comprising an air-passage member, an attached knuckle and interposed insulation, conductors leading independently to terminal contact-plates disposed in staggered relation, so as to give double contact

when the heads are coupled, and terminal contacts so disposed on the air-passage member and the attached knuckle, respectively. 25

3. Combined with a train-pipe, a head for each end thereof, comprising an air-passage member cored for an electric conductor, an adjacent knuckle similarly cored, insulation separating the two members electrically, independent conductors in said cored passages, and contact terminals therefor, said terminals being disposed in staggered order, whereby in coupling a pair of heads the terminals of the air-passage member and 30 the knuckle member, each side, are respectively brought into contact. 35

In testimony whereof I affix my signature in presence of two witnesses.

ALBERT J. CAMPBELL.

Witnesses:

A. T. COOPER,
J. M. ST. JOHN.
